(57) **CLAIM**

The ornamental design for shock body with bypass, substantially as shown and described.

DESCRIPTION

FIG. 1 is a front perspective view of the shock body with bypass in accordance with a first embodiment;
FIG. 2 is a bottom perspective view of the shock body with bypass of FIG. 1;

FIG. 3 is a left side elevation view of the shock body with bypass of FIG. 1;

FIG. 4 is a right side elevation view of the shock body with bypass of FIG. 1;

FIG. 5 is a front side elevation view of the shock body with bypass of FIG. 1;

FIG. 6 is a rear elevation view of the shock body with bypass of FIG. 1;

FIG. 7 is a top view of the shock body with bypass of FIG. 1;

FIG. 8 is a top view of the shock body with bypass of FIG. 1;

FIG. 9 is a front perspective view of the shock body with bypass in accordance with a second embodiment;

FIG. 10 is a bottom perspective view of the shock body with bypass of FIG. 9;

FIG. 11 is a left side elevation view of the shock body with bypass of FIG. 9;

FIG. 12 is a right side elevation view of the shock body with bypass of FIG. 9;

FIG. 13 is a front side elevation view of the shock body with bypass of FIG. 9;

FIG. 14 is a rear elevation view of the shock body with bypass of FIG. 9;

FIG. 15 is a top view of the shock body with bypass of FIG. 9;

FIG. 16 is a top view of the shock body with bypass of FIG. 9;

FIG. 17 is a front perspective view of the shock body with bypass in accordance with a second embodiment;

FIG. 18 is a bottom perspective view of the shock body with bypass of FIG. 17;

FIG. 19 is a left side elevation view of the shock body with bypass of FIG. 17;

FIG. 20 is a right side elevation view of the shock body with bypass of FIG. 17;

FIG. 21 is a front side elevation view of the shock body with bypass of FIG. 17;

FIG. 22 is a rear elevation view of the shock body with bypass of FIG. 17;

FIG. 23 is a top view of the shock body with bypass of FIG. 17; and,

FIG. 24 is a top view of the shock body with bypass of FIG. 17.

(Continued)

The dashed broken lines shown in the drawings depict portions of the shock body with bypass that form no part of the claimed design.
